UNITED STATES PATENT OFFICE.

MAX H. FISCHER, OF EAST ORANGE, NEW JERSEY.

CLUTCH.

No. 13,009.

Specification of Reissued Letters Patent. Reissued Aug. 17, 1909.

Original No. 700,412, dated May 20, 1902, Serial No. 76,366. Application for reissue filed April 2, 1907.
Serial No. 366,047.

To all whom it may concern:

Be it known that I, MAX H. FISCHER, a citizen of the United States, residing at East Orange, in the county of Essex and State of New Jersey, have invented new and useful Improvements in Clutches, of which the following is a specification.

This invention relates more particularly to a clutch which is intended to permit the free movement of a rod, bar, or the like lengthwise in one direction relative to the clutch and to prevent the movement of the rod or bar in the opposite direction. The clutch is useful as a means for locking a rod or bar in a socket or surrounding member so as to permit the insertion of the bar into the socket, but prevent the withdrawal of the rod or bar from its socket without releasing the clutch.

20 The object of the invention is to provide a simple clutch device for the described purpose which will be strong and durable, which will act quickly to positively grip and hold the rod or bar, and which can be easily operated to release the rod or bar.

In the accompanying drawings, which illustrate a clutch comprising the preferred form of my invention, Figure 1 is a longitudinal sectional view of a clutch, illustrating a preferred form of my invention and showing the normal position of the parts. Fig. 2 is a similar view showing the position of the parts when a rod, bar, or the like is gripped by the clutch. Fig. 3 is a transverse sectional view in line 3 3, Fig. 1. Fig. 4 is a similar view in line 4 4, Fig. 2. Fig. 5 is a longitudinal section of a modified form of the clutch. Fig. 6 is a transverse sectional view in line 6 6, Fig. 5. Fig. 40 7 is a side elevation of the device shown in Fig. 5.

Like letters of reference refer to like parts in the several figures.

Referring to Figs. 1 to 4 of the drawings, 45 A designates an inclosing casing or holder for the several parts of the clutch. The casing shown in said figures is in the form of a hollow cylinder having centrally arranged in one end a hole a, the outer portion of which is preferably enlarged or flared to permit the more ready insertion therein of the rod or bar B. The opposite end of the casing is provided with an external screw-thread for the engagement of a screw-cap 50 A', which is made removable for the pur-

pose of assembling and removing the parts of the clutch. The casing is provided with an internal conical face a', which tapers toward the hole a in the end of the casing and the smallest diameter of which is preferably larger than the diameter of the hole a in order to provide a shoulder or face a''. The conical face is not essential, as one or more inclined faces will serve the purpose. C indicates a spring-pressed carrier, which 65 is provided with a central bore or hole c, which is aligned with and of substantially the same diameter as the hole a in the end of the casing. The carrier is also provided with lateral holes or pockets c', intersecting the bore c and in which are confined gripping devices d, which ride on the conical face a' and are of a size sufficient to protrude from the pockets into the bore c when the spring-pressed carrier forces them toward the small 75 end of the conical face a'. Any suitable spring may be employed for moving the carrier forward, a coil-spring E being shown arranged between the screw-cap A' and the inner end c'' of the carrier. The shape of 80 the carrier is immaterial, though that shown, which is frusto-conical, is desirable, inasmuch as the base of the cone slides on the inner wall of the casing and is guided thereby. The number and shape of the 85 gripping devices may be varied, three spheres or balls being preferred in the clutch shown in Figs. 1 to 4, and preferably the inner ends of the pockets c' are smaller in diameter than the largest diameter of the 90 gripping devices in order to prevent the escape of the latter from the pockets into the bore c. c³ indicates an operating-stem for the carrier for moving the same away from the conical face a', so as to permit the gripping devices to recede from and release the 95 rod or bar. The stem, as shown, consists of a tubular sleeve extending through a central opening in the screw-cap A' and is provided at its outer end with a knob or head c⁴. The 100 bore of the stem forms a continuation of the bore c of the carrier and may, if desired, extend entirely through the stem, as shown, so as to permit the use of the clutch on a long rod or bar between its ends.

The operation of the clutch is substantially as follows: Assuming the parts to be in their normal position, (shown in Fig. 1), with the carrier pressed against the shoulder a'' and the gripping device protruding into 110

the bore c of the carrier, when the end of the rod or bar B is inserted through the opening a into the carrier its passage will be obstructed by the protruding gripping devices. 5
5 By pushing on the rod the gripping devices and carrier are moved against the action of the spring E , and the gripping devices are permitted to recede into the pockets, into which they are forced by the rod or bar B , 10 which is then permitted to slide past the gripping devices. When it is attempted to move the rod or bar in the opposite direction, the gripping devices, which are held in engagement with the sides of the rod by the 15 spring-pressed carrier tending to move them on the conical face a' , will by reason of their frictional contact with the rod be drawn along the conical face a' , toward the small end thereof, and will wedge tightly between 20 the rod or bar and the conical face a' , thus effectually holding the rod or bar against movement in that direction.

The construction of the device shown in Figs. 5 to 7 shows the clutch slightly modified and more especially adapted for use in connection with a flat or thin bar or strip. In said Figs. 5 to 7 the casing A^2 is rectangular in cross-section and is provided with a narrow opening a^3 in one end, through 25 which the bar or strip B' is adapted to be inserted into the opening c^6 in the carrier c^6 , which is provided with elongated rollers d' confined in pockets in the carrier and working against inclined faces a^4 on the casing. 30
35 h indicates a flat spring located between the rear end of the casing and the rear end of the carrier for holding the carrier forward in its normal position. l indicates the operating-stem, which is shown to project from 40 one side of the carrier out through a slot in one side of the casing. The operation of the clutch shown in Figs. 5 to 7 is substantially the same as that of the device shown in Figs. 1 to 4.

45 I claim as my invention—

1. In a clutch, the combination with a casing having an interiorly inclined face, a carrier movable longitudinally with regard to said casing, a gripping device carried by 50 said carrier and having its lateral movement controlled by the longitudinal movement of the carrier, and a manually operated device projecting from one end of the casing and

movable outwardly and away from the casing, to release the gripping device. 55

2. The combination with a casing having a hole in one end and an internal inclined face converging toward said hole, of a carrier within the casing having a bore substantially in alignment with the said hole in the casing and also provided with a lateral aperture leading from the bore to its outer surface, a gripping device in said lateral hole working on said incline in the casing and normally obstructing the bore of the carrier, means for forcing said carrier toward the inclined face, and an operating stem connected to said carrier and projecting through the opposite end of the casing for moving the carrier away from said inclined face. 60
65
70

3. The combination with a casing having a hole in one end and an internal inclined face converging toward said hole, of a carrier within the casing having a bore substantially in alignment with the said hole in the casing and also provided with a lateral aperture leading from the bore to its outer surface, a gripping device in said lateral aperture bearing on said incline and normally obstructing the bore of the carrier, an operating stem for said carrier projecting through an opening in the opposite end of the casing and having a bore aligned with the bore of the carrier, a coil spring surrounding said operating stem and confined between the carrier and the casing, and means on said operating stem adapted to permit the fingers of the user to apply pressure between it and the casing. 75
80
85
90

4. In a clutch, a casing having an insertion opening, a gripping device separate from the casing and movable longitudinally relatively thereto, operating means connected to said gripping device and projecting from the end of the casing opposite to the insertion opening, and means for automatically forcing the gripping device toward the insertion opening. 95

In witness whereof, I have hereunto subscribed my name in the presence of two subscribing witnesses.

MAX H. FISCHER.
